UNITED STATES PATENT OFFICE.

GEORGE FRANK TOWNSEND, OF GERMANTOWN, PENNSYLVANIA, ASSIGNOR TO JOHN G. CHAPMAN, OF NEW YORK, N. Y.

DESIGN FOR LACE.

59,569.

Specification for Design.

Patented Nov. 1, 1921.

Application filed June 9, 1921. Serial No. 476,350. Term of patent 3½ years.

To all whom it may concern:

Be it known that I, G. FRANK TOWNSEND, a citizen of the United States, residing in Germantown, county of Philadelphia, and State of Pennsylvania, have invented a new, original, and ornamental Design for Lace, of which the following is a specification, refer-

ence being had to the accompanying drawing, forming part thereof.

The figure is a plan view of the lace showing my new design.

I claim:

The ornamental design for lace as shown.
GEORGE FRANK TOWNSEND.
